(57) **CLAIM**

We claim the ornamental design for an electronic device, as shown and described.

DESCRIPTION

FIG. 1 is a front perspective view of an electronic device showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of an electronic device showing our new design according to a second embodiment;

FIG. 9 is a front view thereof;

FIG. 10 is a rear view thereof;

FIG. 11 is a left-side view thereof;

FIG. 12 is a right-side view thereof;

FIG. 13 is a top plan view thereof;

FIG. 14 is a bottom plan view thereof;

FIG. 15 is an enlarged view of the encircled portion in FIG. 5;

FIG. 16 is an enlarged view of the encircled portion in FIG. 6;

FIG. 17 is an enlarged view of the encircled portion in FIG. 11; and,

FIG. 18 is an enlarged view of the encircled portion in FIG. 13.

The evenly-dashed broken lines in the figures depict portions of the electronic device which form no part of the claimed design.

The dot-dash broken lines in the figures represent a boundary of the claimed design and form no part thereof.

The dot-dash broken lines encircling portions of the electronic device design in FIGS. 5, 6, 11, 13 and 15 through 18 illustrate portions of the claimed design in enlargements and form no part thereof.
